Primary Examiner — Cynthia R Underwood*(74) Attorney, Agent, or Firm* — Kirk A. Buhler; Buhler & Associates**CLAIM**

The ornamental design for a rope line anchor with hook, as shown and described.

DESCRIPTION

FIG. 1 is a front perspective view of a rope line anchor with hook showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a rear elevation view thereof;

FIG. 7 is a front elevation view thereof; and,

FIG. 8 is a rear perspective view shown in an environment of use.

The broken lines in FIG. 8 depict environmental subject matter of a rope and forms no part of the claimed design
